UNITED STATES PATENT OFFICE.

FRANK STOKLOSA, OF CHICAGO, ILLINOIS.

PUMP.

1,346,989.

Specification of Letters Patent.

Patented July 20, 1920.

Application filed January 21, 1920. Serial No. 353,000.

To all whom it may concern:

Be it known that I, FRANK STOKLOSA, a citizen of Poland, residing at Chicago, in the county of Cook and State of Illinois, have 5 invented certain new and useful Improvements in Pumps, of which the following is a specification.

The primary object of the present invention resides in the provision of a pump of 10 the lift type wherein the piston within the pump cylinder for elevating the water is raised and lowered by an oscillatory movement of an operating handle operatively connected to the piston.

15 A further object of the invention is to associate a weighted lever with a lift pump to equalize pressure during the raising and lowering movement of the pump piston.

With the above and other objects in view, 20 the invention consists in the novel form, combination and arrangement of parts herein fully described and shown in the accompanying drawing, wherein like reference characters indicate similar parts throughout 25 the several views.

In the drawings,

Figure 1 is a front elevational view of a 30 lift pump constructed in accordance with the present invention, the lower portion of the pump cylinder being broken away,

Fig. 2 is a vertical cross sectional view of the pump shown in Fig. 1 showing the lift piston within the pump cylinder,

Fig. 3 is a cross sectional view taken on 35 line III—III of Fig. 2 with the valve positioned above the piston head, and

Fig. 4 is a cross sectional view taken on line IV—IV of Fig. 2 with a portion of the piston head broken away.

40 The invention relating to water pumps of the lift type, there is illustrated a pump cylinder 5 adapted for sinking in a well with the head 6 of the cylinder secured to the well cover 7 by the lateral flange 8 shown more 45 clearly in Fig. 1, while an outlet spout 9 arranged adjacent the upper end of the cylinder head 6 is adapted for the delivery of water from the pump cylinder.

40 The mechanism for elevating the water in the pump cylinder 5 embodies a hollow piston 10 of the form best illustrated in Fig. 2, the piston and cylinder being preferably rectangular in cross section to prevent relative rotary movement between the parts. The 55 upper end 10' of the piston 10 is provided with water passage openings 11 that are nor-

mally closed by a flat valve 12 shown in Figs. 3 and 4, the valve 12 having a central opening therein to loosely receive the central boss 13 in the top 10' of the piston. Guide 60 pins 14 extending vertically from the upper end 10' of the piston form guides for the vertical movements of the flat valve 12 while the heads of said pins 14 limit the upward movement of the valve. A piston rod 15 is 65 connected to the piston boss 13 and projects upwardly of the head 6 of the pump.

In order to effect a reciprocation of the piston 10 within the pump cylinder 5, there is provided a frame mounted upon the pump 70 head 6 which comprises vertical bars 16 and 17 between which the lever beam 18 is pivoted as at 19, an adjustable weight 20 being mounted on each end of the lever beam 18 for purposes of weighting and counterbalancing the same. A vertical end extension 21 is carried by the lever beam 18, being braced as at 21' and has a lateral extension 22 connected by a cord or cable 23 to the upper end of the piston rod 15, the cord 23 80 passing over a pulley 24 mounted in the bearing 25 at the upper end of the side bars 16 and 17. A sprocket wheel 26 operated by a crank 27 is journaled on the front face of the cylinder head 6 and a point above the 85 outlet spout 9 while sprocket wheels 28 are journaled at opposite sides of the spout, and over all of which sprocket wheels passes a sprocket chain 29 with the ends connected to cords 30 carried by opposite ends of the 90 lever beam 18.

In the operation of the pump, the crank handle 27 is oscillated to follow the path shown by the curved arrow line in Fig. 1 to effect a rising and lowering of the opposite 95 ends of the lever beam 18 with a consequent rise and fall of the piston 10 within the cylinder 5. During the lowering movement of the piston, caused by its end weight when the arm extension 21 of the lever beam is 100 elevated, the valve 12 moves vertically upon the pins 14 to permit the water in the lower end of the cylinder to pass through the piston openings 11, while during a reverse movement of the lever beam 18, with the 105 rise of the piston 10, the valve 12 seats directly upon the upper end 10' of the piston to elevate the water within the cylinder above the piston for delivery by way of the outlet spout 9. The adjustable weights 20 110 upon the lever beam 18 insure an easy operation of the pump by counterbalancing the

2
oscillating movements of the operating crank 27.

While there is herein shown and described, the preferred embodiment of the invention, it is nevertheless to be understood that minor changes may be made in the novel form, combination and arrangement of parts without departing from the spirit and scope of the invention as hereinafter 10 claimed.

What is claimed as new is:

A lift pump of the type described comprising a pump cylinder, a piston reciprocable within said cylinder and means for 15 raising and lowering said piston, said means

including a lever beam pivoted above the pump cylinder, an angle extension carried by one end of the lever beam, a piston rod carried by the piston, a flexible connection between the lever extension and piston rod, 20 a plurality of sprocket wheels rotatably supported upon the pump cylinder, a sprocket chain passing over said sprocket wheels and connected to said lever beam and means for operating the wheels to oscillate the lever beam to raise and lower the piston in the cylinder. 25

In testimony whereof I affix my signature.

FRANK STOKLOSA.
